ELECTRICAL PRECIPITATOR

Archibald F. Meston, Middlesex Borough, N. J.,
assignor to Research Corporation, New York,
N. Y., a corporation of New York

Application March 2, 1935, Serial No. 9,118

20 Claims.

(Cl. 183—7)

This invention relates to apparatus for the electrical treatment of gases and other fluids and particularly to apparatus for the precipitation of suspended particles from gaseous fluids by passing the gaseous fluids between opposed complementary electrodes between which a relatively high potential difference is maintained.

Typically in such apparatus one electrode presents an extended surface and is known as a collecting electrode, while the complementary electrode, known as a discharge electrode, presents edges, points or portions of high radius of curvature which facilitate the formation of corona discharge.

15 A principal object of the invention is to provide electrical precipitation apparatus of high efficiency and compact arrangement.

A further object is to provide a precipitator in which the gas to be treated enters the apparatus and the treated gas leaves the apparatus in parallel directions, while the gas passes through the treating zone between the electrodes at right angles to the direction of inlet and outlet of the gases, and particularly to provide 25 a precipitator in which the gases enter and leave the precipitator vertically but pass horizontally between the treating electrodes.

30 A further object is to provide a vertical flow precipitator in which the precipitated particles fall at right angles to the gas flow rather than counter to the gas flow as in ordinary vertical flow precipitators.

A still further object is to provide a vertical flow precipitator in which the gas flow is distributed uniformly throughout the area of the 35 treating zone.

Another object of the invention is to provide a precipitator in which centrifugal action supplements the action of the electrical field in removing suspended particles from the gases treated 40 therein.

These and other objects and advantages which will be apparent from the description of the invention are effected by means of the invention 45 which broadly comprises a construction including opposed complementary electrodes positioned within a casing, and inlet and outlet conduits projecting into the interior of said casing and opening into the space between said electrodes 50 at substantially opposite points in said casing. In some embodiments of the invention, the inlet and outlet conduits are provided by the discharge electrode members or by the collecting electrode members.

55 In embodiments of the invention in which the

electrode members are concentrically arranged to provide annular paths therebetween, the inlet conduits preferably open into said annular paths at points spaced circumferentially along the paths from the outlets to the eduction conduits so that the gases in passing from the inlet to the outlet openings are subjected to centrifugal action.

Typically in such apparatus one electrode presents an extended surface and is known as a collecting electrode, while the complementary electrode, known as a discharge electrode, presents edges, points or portions of high radius of curvature which facilitate the formation of corona discharge.

10 A principal object of the invention is to provide electrical precipitation apparatus of high efficiency and compact arrangement.

A further object is to provide a precipitator in which the gas to be treated enters the apparatus and the treated gas leaves the apparatus in parallel directions, while the gas passes through the treating zone between the electrodes at right angles to the direction of inlet and outlet of the gases, and particularly to provide 25 a precipitator in which the gases enter and leave the precipitator vertically but pass horizontally between the treating electrodes.

Fig. 12 is a partial sectional elevation of the embodiment of Fig. 11;

Fig. 13 is a horizontal section on line 13—13 of Fig. 11; and

Fig. 13a is a horizontal section showing a modification of the construction of Figs. 11—13.

Figs. 1, 2 and 3 show a vertical flow precipitator which may be mounted directly on a furnace or boiler as indicated at 1. The precipitator comprises a vertical cylindrical casing 2, 50 within which is mounted the collecting electrode-flue structure 3 and the discharge electrode structure. The discharge electrode structure consists of a plurality of wire discharge elements 4 concentrically positioned between the casing 55

and the collecting surface of electrode-flue structure 3 by means of rings 5. This structure is suspended in the casing and insulated therefrom by bushings 6 and is connected to a source of high potential current at 7.

The collecting electrode-flue structure comprises a cylindrical shell 8, divided by a diagonal partition 9 into two compartments 10 and 11. Each compartment opens into the treating space 10 between the electrodes through a plurality of orifices 12 and 13, the orifices leading from one compartment being diametrically opposite those leading from the other compartment. Compartment 10 is closed at the top and opens at the bottom into the flue 14 carrying the gases to be treated, while compartment 11 is closed at the bottom and opens at the top into the stack 15. Casing 2 and electrode 3 are electrically connected and grounded so that the inner surface of the casing and the outer surface of the electrode shell serve as collecting surfaces.

The gases to be treated pass first into compartment 10, out through orifices 12 into the treating zone between the shell 8 and the casing. The gases pass vertically in both directions through the treating zone to the opposite side of the treater to orifices 13 where they pass into compartment 11 and thence into stack 15. In their passage from orifices 12 to orifices 13, the gases are subjected to the action of the electric field between the electrodes and corona discharge emanating from elements 4 and are also subjected to centrifugal force by reason of their vertical motion. Suspended particles are forced to the collecting surfaces and thence drop into hoppers 16. Dust collecting in the lower part of compartment 11 may be cleaned out through door 17.

Fig. 3a shows a modification which may be substituted for the collecting electrode-flue structure of Figs. 1-3. In this construction, the collecting electrode structure is divided into a plurality of flues 21, and a central flue 22. As shown, the gases to be treated enter central flue 22, pass out into the treating zone through a plurality of circumferentially spaced orifices 23, and thence into flues 21 through orifices 24, which alternate with orifices 23. 2' is the precipitator casing and 4' are discharge elements.

In the embodiment shown in Figs. 4, 5 and 6, a plurality of parallel collecting electrode-flue members 31 alternate with discharge electrode members 32 in casing 33.

The collecting electrode members 31, which are connected to the casing 33 and to ground, comprise hollow rectangular chambers divided into compartments 34 and 35 by partitions 36. Compartment 34 communicates at the top with supply flue 37 and compartment 35 communicates with eduction flue 37a, while both sets of compartments open at their outer ends into the interior of the precipitator casing.

The discharge electrode members consist of discharge elements 38 suspended between bars 39 and suspended in the casing and insulated therefrom by bushings 40.

The gas to be treated passes into compartments 34 from flue 37, thence out the ends into the interior of the precipitator casing. At this point, the gases make a sharp reverse turn, which tends to throw out suspended particles, thence through the length of the treating zones between the electrodes, and after making a sharp reverse turn at the other end of the precipitator chamber, they pass into compartments 35 and out into flue 37a.

The precipitated material falls into hoppers 41.

In the alternate form shown in Fig. 7, the collecting electrode structure is composed of two separate sets of compartments 34' and 35', longitudinally spaced apart. In the space between the pairs of compartments, it is advantageous to position electrode cleaning means, such as rappers 42.

In the construction shown in Figs. 8, 9 and 10, the gases are brought into and out of the interior of precipitator casing 51 by means of a flue structure located in the central portion of the interior between two sets of opposed electrode systems and opening into opposite ends of the interior of the casing. This flue structure is formed of vertical members 52 and diagonal member 53 which provide a chamber 54 opening at the bottom into inlet stack 55 and at the side into one end of the interior of the casing, and a chamber 56 opening at the top into outlet stack 57 and at the side into the opposite end of the interior of the casing.

The collecting electrodes comprise flat plate-like members 58 connected to the casing and to ground. The interior surfaces of casing 51 and the exterior surfaces of members 52 also serve as collecting surfaces. To facilitate the distribution of gases, the collecting electrode members 58 decrease in length towards the middle portion of the precipitator, and to avoid corona discharge from the edges of the members, the edges are preferably rounded.

Alternating with the collecting electrodes are discharge electrode structures consisting of discharge elements 59 carried between frames 60 which are suspended in the casing and insulated therefrom by bushings 61.

Precipitated material is collected in hoppers 62.

In the construction illustrated in Figs. 11, 12 and 13, the inlet and outlet flues are provided by the discharge electrode structure. In this construction, a cylindrical collecting electrode member 71 is concentrically positioned within casing 72 and insulated therefrom by means of bushings 73. The discharge electrode structure is concentrically mounted within the collecting electrode. The discharge electrode comprises a cylindrical shell 74 divided into two compartments 75 and 76 by means of partition 77. Compartment 75 is closed at the top and opens at the bottom into inlet stack 78, while compartment 76 is closed at the bottom and opens at the top into outlet stack 79. Compartment 75 communicates with the interior of the casing through a vertical row of orifices 80, while compartment 76 communicates with the interior of the casing through a diametrically opposite row of orifices 81. Positioned around the exterior of discharge electrode shell 74 are a plurality of longitudinal discharge elements 82, for example in the form of fins 60 welded to the shell 74.

Gases passing into compartment 75 from inlet stack 78 pass out into the treating zone through orifices 80, thence vertically in both directions through the annular treating zone to the opposite side where they pass out through orifices 81 into compartment 76 and thence into outlet stack 79. In the passage of the gases through the treating zone, the suspended particles are thus subjected to both centrifugal and electrical action. The precipitated material is caught in hoppers 83.

In Fig. 13a, there is shown an alternate form of discharge electrode-flue structure which may be used in the construction of Figs. 11-13. In 75

this structure, the discharge electrode is divided into a plurality of compartments 91 surrounding a central compartment 92. When the central compartment is used as an inlet conduit, the outer compartments serve as outlet conduits. In this case, the compartment 92 is closed at the top and communicates at the bottom with a supply stack, and the compartments 91 are closed at the bottom and communicate at the top with an outlet stack. The gases to be treated pass into the treating zone through orifices 93 and leave the treating zone through orifices 94.

It will be seen from the forms of the invention illustrated and described that the principles of the invention may be embodied in a wide variety of constructions and methods of operation.

I claim:

1. Apparatus for electrically treating gases comprising a casing, opposed vertically extending complementary electrodes within said casing, certain of said electrodes providing inlet and outlet conduits vertically projecting into the interior of said casing and opening into the space between said electrodes at substantially horizontally opposite points in said casing, whereby gaseous fluid may be introduced into said casing and removed therefrom in parallel vertical directions and caused to pass between said electrodes in a horizontal direction substantially at right angles to the direction of inlet and exit of the gaseous fluid and the gravity removal of separated materials is effected at right angles to the flow of gases.

2. Apparatus for electrically treating gases comprising a casing, opposed complementary electrodes within said casing providing a horizontal path for the flow of gases therebetween, and providing inlet and outlet conduits vertically projecting into the interior of said casing and opening into the space between said electrodes at opposite ends of said path, whereby gaseous fluid may be introduced into said casing and removed therefrom in parallel vertical directions and caused to pass between said electrodes in a horizontal direction substantially at right angles to the direction of inlet and exit of the gaseous fluid and the gravity removal of separated materials is effected at right angles to the flow of gases.

3. Apparatus for electrically treating gases comprising a casing, opposed complementary electrodes within said casing providing an annular path for the flow of gases therebetween, and providing inlet and outlet conduits projecting into the interior of said casing and opening into the space between said electrodes at opposite points in said path, whereby gaseous fluid may be introduced into said casing and removed therefrom in parallel directions and caused to pass between said electrodes substantially at right angles to the direction of inlet and exit of the gaseous fluid.

4. Apparatus for electrically treating gases comprising a casing, opposed parallel complementary electrodes within said casing providing a path for the flow of gases therebetween, and providing inlet and outlet conduits projecting into the interior of said casing and opening into the space between said electrodes at opposite ends of said path, whereby gaseous fluid may be introduced into said casing and removed therefrom in parallel directions and caused to pass between said electrodes substantially at right angles to the direction of inlet and exit of the gaseous fluid.

5. Apparatus for electrically treating gases comprising a casing, opposed complementary electrode systems within said casing providing a plurality of parallel paths for the flow of gases therebetween, and providing inlet and outlet conduits projecting into the interior of said casing and opening into the space between said electrode systems at opposite ends of said paths, whereby gaseous fluid may be introduced into said casing and removed therefrom in parallel directions and caused to pass between said electrodes substantially at right angles to the direction of inlet and exit of the gaseous fluid.

6. Electrical precipitation apparatus comprising a casing, opposed complementary electrode systems within said casing providing a path for the flow of gases therebetween, one of said electrode systems providing a plurality of conduits opening into said casing from the exterior thereof at mutually remote points.

7. Electrical precipitation apparatus comprising a casing, opposed complementary electrode systems within said casing providing a path for the flow of gases therebetween, one of said electrode systems providing inlet and outlet conduits opening into said casing from the exterior thereof at opposite ends of said path.

8. Electrical precipitation apparatus comprising a casing, opposed complementary electrode systems within said casing providing an annular path for the flow of gases therebetween, one of said electrode systems providing inlet and outlet conduits opening into said casing at opposite points in said path.

9. Electrical precipitation apparatus comprising a casing, opposed concentric complementary electrode systems within said casing providing an annular path for the flow of gases therebetween, one of said electrode systems providing inlet and outlet conduits opening into said casing at opposite points in said path.

10. Electrical precipitation apparatus comprising a casing, opposed discharge and collecting electrode systems within said casing providing a path for the flow of gases therebetween, said discharge electrode system providing inlet and outlet conduits opening into said casing at opposite ends of said path.

11. Electrical precipitation apparatus comprising a casing, opposed discharge and collecting electrode systems within said casing providing a path for the flow of gases therebetween, said collecting electrode system providing inlet and outlet conduits opening into said casing at opposite ends of said path.

12. Electrical precipitation apparatus comprising a casing, opposed complementary electrode systems within said casing providing a plurality of parallel paths for the flow of gases therebetween, one of said electrode systems providing inlet and outlet conduits opening into said casing from the exterior thereof at opposite ends of said paths.

13. Electrical precipitation apparatus comprising a casing, opposed complementary electrode systems within said casing providing a plurality of parallel horizontal paths for the flow of gases therebetween, one of said electrode systems providing inlet and outlet conduits opening into said casing from the exterior thereof at horizontally opposite ends of said paths.

14. Electrical treating apparatus comprising a casing, opposed discharge and collecting electrode systems concentrically disposed within said casing so as to provide an annular path therebe-

- tween, the innermost of said electrode systems providing a plurality of inlet and outlet conduits opening into said annular path at alternately spaced points.
- 5 15. Electrical treating apparatus comprising a casing, opposed discharge and collecting electrode systems concentrically disposed within said casing so as to provide an annular path therebetween, the innermost of said electrode systems 10 providing an inlet and an outlet conduit opening into said annular path at opposite points.
16. Apparatus for the electrical purification of gases comprising a casing, opposed discharge and collecting electrode systems within said casing, 15 one of said electrode systems providing a shell, means dividing said shell into a plurality of compartments, certain of which provide inlet conduits for the gases to be treated and others of which provide eduction conduits for the treated gases, 20 said inlet and eduction conduits opening into the interior of said casing at mutually remote points, means for conveying gases to be treated to said inlet conduits and means for conveying treated gases from said outlet conduits.
- 25 17. Apparatus for the electrical purification of gases comprising a casing, opposed discharge and collecting electrode systems within said casing, one of said electrode systems forming the external walls of a chamber, means dividing said 30 chamber into two non-communicating compartments, openings from said compartments into the interior of said casing at mutually remote points, means for conveying gases to be treated into one of said compartments and means for 35 conveying treated gases from the other of said compartments.
18. Apparatus for the electrical purification of gases comprising a casing, opposed discharge and collecting electrode systems within said casing, said discharge electrode system defining a chamber, means dividing said chamber into two non-communicating compartments, openings from said compartments into the interior of said casing at mutually remote points, means for conveying gases to be treated into one of said compartments and means for conveying treated gases from the other of said compartments. 5 10
19. Apparatus for the electrical purification of gases comprising a casing, opposed discharge and collecting electrode systems within said casing, 15 said collecting electrode system defining a chamber, means dividing said chamber into two non-communicating compartments, openings from said compartments into the interior of said casing at mutually remote points, means for conveying gases to be treated into one of said compartments and means for conveying treated gases from the other of said compartments. 20 25
20. Apparatus for the electrical purification of gases comprising a casing, opposed concentric discharge and collecting electrode systems within 25 said casing, the innermost of said electrode systems defining a chamber, means dividing said chamber into two non-communicating compartments, openings from said compartments into the interior of said casing at mutually remote points, 30 means for conveying gases to be treated into one of said compartments and means for conveying treated gases from the other of said compartments. 35

ARCHIBALD F. MESTON. 35
